United States Patent Office

Des. 181,234
Patented Oct. 15, 1957

181,234

TELEVISION ANTENNA

Roger Mark Singer, New York, N. Y., assignor to Snyder Manufacturing Company, Philadelphia, Pa., a corporation of Pennsylvania

Application December 6, 1956, Serial No. 44,080

Term of patent 7 years

(Cl. D26—14)

FIG. 1.

FIG. 2.

FIG. 3.

Fig. 1 is a fragmentary perspective view of a television antenna, showing my new design;

Fig. 2 is a fragmentary front elevational view to a larger scale, and

Fig. 3 is a fragmentary side elevational view thereof, to a larger scale.

A portion of the antenna has been broken away in the drawing figures for convenience of illustration.

I claim:

The ornamental design for a television antenna, as shown and described.
